[57] CLAIM

The ornamental design for a coat hanger, as shown and described.

DESCRIPTION

FIG. 1 is a front view of the coat hanger showing the new and ornamental design;

FIG. 2 is a rear view of the coat hanger of FIG. 1;

FIG. 3 is a left side view of the coat hanger of FIG. 1, the right side being a mirror image except for the hook area;

FIG. 4 is a reduced front perspective view of the coat hanger of FIG. 1;

FIG. 5 is a reduced rear perspective view of the coat hanger of FIG. 1; and,

FIG. 6 is a reduced rear perspective view of the coat hanger of FIG. 1 which shows a moveable portion of the coat hanger in an alternate position.
